ATTORNEY

UNITED STATES PATENT OFFICE.

LOYD F. BLASSINGHAM, OF BARRON, WISCONSIN.

DESIGN FOR AN AUTOMOBILE-BODY.

50,602.

Specification for Design.

Patented Apr. 17, 1917.

Application filed February 2, 1917. Serial No. 146,289. Term of patent 14 years.

To all whom it may concern:

Be it known that I, LOYD F. BLASSINGHAM, a citizen of the United States, residing at Barron, in the county of Barron and State of Wisconsin, have invented a new, original, and ornamental Design for Automobile-Bodies, of which the following is a specification, reference being had to the accompanying drawings, forming part thereof.

Figure 1 is a plan view of an automobile body, showing my new design.

Fig. 2 is a fragmentary sectional view.

I claim:—

The ornamental design for an automobile body, as shown.

LOYD F. BLASSINGHAM.
